UNITED STATES PATENT OFFICE.

WILLIAM H. SCHUYLER, OF CHICAGO, ILLINOIS.

PRINTER'S GALLEY.

SPECIFICATION forming part of Letters Patent No. 783,899, dated February 28, 1905.

Application filed June 8, 1904. Serial No. 211,241.

To all whom it may concern:

Be it known that I, WILLIAM H. SCHUYLER, a citizen of the United States of America, residing at Chicago, in the county of Cook and State of Illinois, have invented certain new and useful Improvements in Printers' Gallies, of which the following is a description.

My invention belongs to that well-known class of devices known as "printers' gallies," to which the set type are transferred from the composing-stick or otherwise in making up the form or taking it down. It is often used in taking a proof of the set matter.

The object of my improvement is to produce a galley which shall be strong and durable in its construction and shall not by use be broken or easily warped or sprung out of its proper form.

To this end my invention consists in the novel construction, arrangement, and combination of parts herein shown and described, and more particularly pointed out in the claims.

In the drawings, wherein like reference characters indicate like or corresponding parts, Figure 1 is a perspective view showing a complete galley embodying my improvement. Fig. 2 is a partial side elevation with parts broken away and in which the wall and bottom are slightly separated to more clearly show the construction. Fig. 3 is a modified form of the wall with parts broken away to show the construction, and Fig. 4 is a sectional view illustrating the manner in which the parts are firmly locked together.

In the drawings, 1 represents the bottom of the galley, provided with a plurality of apertures 2, arranged about the margin on the line where the walls will be located.

3 represents the wall of the galley, which is formed of a single bar, either by casting, forging, or otherwise, and provided with a plurality of lugs 4, projecting from one edge of the wall and adapted to be seated in the apertures 2. The lugs are of sufficient length and the wall is of such material that when the bottom is suitably positioned the lugs may be headed or riveted down thereupon, firmly binding the parts together. In the preferred

construction the side walls are integral, as indicated, preventing the breaking of the walls at the angles, and the lugs 4 are also formed integral with the wall.

In operation I have used brass for the material in making up the galley, and the walls 3 have been cast, the lugs being cast thereupon at the same time. In construction, also, the apertures 2 are preferably countersunk to receive the head of the rivet and form a flush finish on the under surface of the bottom. 60

Fig. 3 shows a modification in which threaded holes are tapped out in the edge of the walls, as at 5, and the lugs are screw-threaded to fit therein, as at 6. Obviously this would be the more expensive method of forming the 65 galley, and at the same time the union between the wall and the bottom would not be as firm as though the lugs were formed integral with the walls. It is obvious that if preferred the walls 3 may be formed to inclose only three 70 sides thereof, as shown in the drawings.

In practice I have found this form of galley very strong and durable and particularly adapted to the heavy work for which it is intended.

It is well known that as soon as a galley gets out of line or is twisted it is not suitable for the purpose for which it is intended. My invention is particularly adapted to prevent this, as well as to prevent the breaking apart of the 80 walls at the angles. My galley is formed of two parts firmly locked together, the integral wall greatly strengthening the entire structure.

Having thus described my invention, what 85 I claim as new, and desire to secure by Letters Patent, is—

1. A printer's galley comprising a bottom plate provided with marginal perforations, in combination with inclosing walls comprising 90 an integral bar of suitable form provided with lugs projecting from one of its edges registering with and positioned in the perforations in said bottom plate and headed down thereupon, whereby the two are firmly secured together. 95

2. A printer's galley comprising a bottom plate provided with marginal perforations, in

combination with inclosing walls comprising
an integral bar of suitable form provided with
integral lugs projecting from one of its edges
and located in said marginal perforations in
5 said bottom plate and headed down thereupon,
whereby the two are firmly secured together.

In testimony whereof I have hereunto signed

my name in the presence of two subscribing
witnesses.

WILLIAM H. SCHUYLER.
